(57) CLAIM

The ornamental design for a holder for golfballs, golf tees and ball markers, as shown and described.

DESCRIPTION

FIG. 1 is a perspective view of the holder for golf balls, golf tees and ball markers showing my new design;

FIG. 2 is a front view thereof;

FIG. 3 is a left side view thereof, the right side being a mirror image thereof;

FIG. 4 is a top view thereof;

FIG. 5 is a bottom view thereof; and,

FIG. 6 is a rear view thereof.

The broken line showing of environment in FIG. 1 is for illustrative purposes only and forms no part of the claimed design.
